A. A. JUDD

PAPER MAKING MACHINE

Filed March 17, 1922

UNITED STATES PATENT OFFICE.

ALFRED ALBERT JUDD, OF IROQUOIS FALLS, ONTARIO, CANADA, ASSIGNOR OF ONE-HALF TO CHARLES FRANCIS MURTAUGH, OF IROQUOIS FALLS, ONTARIO, CANADA.

PAPER-MAKING MACHINE.

Application filed March 17, 1922. Serial No. 544,422.

To all whom it may concern:

Be it known that I, ALFRED ALBERT JUDD, a subject of the King of Great Britain, residing in Iroquois Falls, in the District of Temiskaming, in the Province of Ontario, Canada, have invented certain new and useful Improvements in Paper-Making Machines, of which the following is a specification.

10 My invention relates to improvements in
paper-making machines, and relates more
particularly to that class of machine used
in the early stages of paper manufacture
when the water is being squeezed or pressed
15 out of the pulp, and the object of my in-
vention is to provide improved means sub-
stantially automatic in character, to remove
the stock or pulp from the top press roll,
and to carry the same intermixed with water
20 to suitable pumping means whereby it is
utilized in the process of manufacturing pa-
per, without delay, and without necessity
of manual help, and in the following speci-
fication I shall describe a disclosure with-
25 in my invention, and what I claim as new
will be set forth in the claims forming part
of this specification.

Fig. 1 is an isometric projection of a conventional form of machine used in making paper in the early stages, showing the same equipped with my invention, Fig. 2 is a vertical cross-section on the line 2—2, Fig. 1, and Fig. 3 is a plan view of a bar herein-after more particularly referred to.

35 In the drawings, like characters of reference refer to the same parts.

In the process of manufacturing paper especially from pulp, the wet pulp is carried between a series of pairs of press rolls by means of a suitable conveyor, in order to remove surplus moisture therefrom, and during this process frequently the pulp becomes attached to the top press roll, and it is necessary to remove this material from this roll so that the machine can properly function. A scraper, known in the trade as a "doctor," is pivotally mounted in association with the top press roll, and one or more attendants are necessary to remove the pulp accumulating on this scraper into a truck, and when this truck is filled it is used to convey this pulp to the mixing room for further use.

Now in putting my invention into practice I pivotally mount a hopper in rela-

tion to the top and bottom press rolls, and provide this hopper with a scraper which rests upon the top roll. Means is provided to supply running water into and through said hopper to carry the pulp removed from this top press roll into a suitable chute whereby it is conveyed to the mixing room to be used over again.

Means is provided whereby the hopper can carry weights so as to regulate the pressure of the scraper against the top press roll. 65

A and B are the top and bottom press rolls respectively, journaled to rotate respectively in any suitable standards C and 70 D. The roll A is usually made of wood, and the roll B is usually covered with rubber compound. Between these rolls is passed the conveyor E, which passes over rollers F suitably journaled. The conveyor 75 E is of course driven in any suitable manner, and as the driving of this conveyor forms no part of my invention, driving means has not been illustrated. In place of the well-known plate-like member upon 80 which the pulp accumulates as removed

which the pulp accumulates as removed from the top roll, I use a hopper G, which is pivotally mounted to co-act with the top press roll A in any suitable manner. The construction disclosed for this purpose comprises a bar H held in brackets I attached to the lower outer side of said hopper, and the ends of this bar are held in the standards C. The scraper or doctor comprises a bar 2 preferably made of wood, and preferably bevelled as shown at 3, and upon referring to Fig. 1, it will be seen that the bevelled edge of the said scraper 2 rests upon the top press roll A, which revolves in the direction indicated by arrow. 4 is the lip of the side 5 of the hopper G, which I preferably form an integral part of said side. Between this lip and the scraper 2 I locate a stiffening bar 6, preferably made of angle iron. The flange 7 of this bar 6 is provided with a plurality of open slots 8 thus forming a plurality of tongues 9. The ends of these tongues are preferably bevelled as shown at 10. The front edge of the lip 4 is also preferably bevelled as shown at 11, although these bevels 10 and 11 are not essential. The bars 2 and 6 are coupled to the lip 4 by any suitable means such as nuts and bolts commonly designated 12. The heads of these bolts rest upon the top 110

of the lip 4, and the bolts pass through the slots 8, and extend through the bar 2 and the nuts screwing on these bolts are located under the bar 2 and of course have plenty 5 of clearance with the roll A.

By any suitable means, such as water pipes 13, water is sprayed continuously into the hopper G and consequently the pulp passing into said hopper flows out of the opening 14 in one end of the hopper and into the spout 15 whence it passes into the chute 16 which carries it to a pump, (not shown) which will convey it to the screens (not shown).

15 A water pipe 17 may also be provided to introduce water through the closed end of the hopper so as to longitudinally flush the same.

This hopper will be preferably inclined to 20 slope towards the opening 14 and so facilitate the passage of the mixed water and pulp into the chute 16.

Though it is not essential to my invention, if desired, I may provide means to regulate the pressure of the scraper bar 2 upon the roll A. Suitable means for this purpose may comprise a bar 18 notched as shown at 19 to rest upon the ends 20 of the hopper so that the position of this bar may 25 be shifted towards or away from the scraper bar 2. This bar 18 may be adapted to support weights 21, for the purpose set forth.

While I have gone into specific details regarding the construction of the various parts 35 of my invention, it must be understood that the construction illustrated is merely exemplary, and is not to be construed in any manner as limiting the scope of my protection as defined in the following claims.

40 22 represents the pulp carried by the conveyor E between the rolls A and B.

It will be observed upon referring especially to Figs. 1 and 2, that the side 5 of the hopper slopes from the roll A towards the

other side of the hopper, thus providing substantially a trough *a* in the bottom of the hopper wherein the pulp and water must collect before these materials pass through the opening 14.

What I claim is:

1. In a paper-making machine, the combination with top and bottom press rolls, and a conveyor suitably mounted and adapted to carry the pulp therebetween, of a hopper adapted to be pivotally mounted, and provided with a scraper adapted to rest upon the said top press roll; means whereby water is passed into said hopper to act as a carrier for the pulp received thereby, thereout of, and adjustable weights carried by 55 said hopper, for the purpose specified.

2. In a paper-making machine, the combination with top and bottom press rolls, and a conveyor suitably mounted and adapted to carry the pulp therebetween, of a hopper 55 adapted to be pivotally mounted at the lower portion of its outer side, and provided with a sloping inner side; a scraper removably carried by the upper edge of said sloping side and adapted to be held by the weight 70 of said hopper in contact with said top press roll, adjustable weights carried by said hopper, and means whereby water is passed into said hopper to carry the pulp received thereinto and out of an opening formed in 75 one end of said hopper.

3. In combination a hopper provided with an opening in one end, and having one side formed to slope inwardly; an outwardly extending lip integrally formed with said sloping side; a bevelled scraper, a stiffening bar located between said lip and said scraper, and means whereby these parts are removably coupled together.

ALFRED ALBERT JUDD.
